UNITED STATES PATENT OFFICE.

ODILON MAZURETTE, OF ALAMEDA, CALIFORNIA.

SAFETY DEVICE FOR BUZZ-PLANERS.

1,371,921.

Specification of Letters Patent. Patented Mar. 15, 1921.

Application filed June 4, 1918. Serial No. 238,130.

To all whom it may concern:

Be it known that I, ODILON MAZURETTE, citizen of the United States, residing at Alameda, in the county of Alameda and State of California, have invented certain new and useful Improvements in Safety Devices for Buzz-Planers, of which the following is a specification.

This invention is a device for guiding the work on a buzz planer or similar apparatus.

One of the objects of the invention is to provide a movable guard positioned over the knives of a buzz planer or similar apparatus in such manner that the hands of the operator are prevented from coming in contact with the knives. A further object is to provide a guard of the character referred to which will accommodate itself to work of different widths.

The invention will be hereinafter fully set forth and particularly pointed out in the claim.

In the accompanying drawings:

Figure 1 is a top plan view of a planer with the guard in position. Fig. 2 is a side elevation of the same. Fig. 3 is an end elevation, and Fig. 4 is an enlarged view of the guard mounting.

Referring to the drawing, 1 indicates the base of a buzz planer of a well known type, and 2 the rotating cylinder which carries the knives, the same being driven by a suitable source of power 3, through the belt 3'. A guide 4 is provided against which the material is forced while being worked, in a manner well known.

Pivoted to the planer table 6 is a guard 5, said table having an angle plate 7, provided with a boss 8 through which the pivot rod 9 passes. Said rod 9 is provided with a plate 10 which is attached to the bottom of the guard in suitable manner, such as by means of the screws 11. This construction enables the guard to be moved in a horizontal plane, and by putting shims between the boss 8 and the plate 10, the guard may be raised to any height above the table, as is shown by the dotted position Fig. 2. In case the guard 5, by reason of its weight should sag, a set screw 19 has been provided in the plate and has one end thereof in abutting engagement with the guard. By adjust-

ment of said screw the guard will be elevated or adjusted relative to the plate to take up 55 the sag. In order to keep a constant pressure on a timber being operated upon, a weight 12 is provided, which is secured to the guard by means of a cable 13, fastened to a hook 14 on the under side of the guard. 60 The cable passes under the table 6, over a pulley 15 and down to the weight 12.

Passing through two eye bolts 16 is a rod 17, which enables the operator to move the guard away from his work and see how 65 it is progressing. This may also be done by means of a knob 18.

The operation of the machine is as follows:

A timber (illustrated in dotted lines, 70 Fig. 1) is pushed along the table, coming in contact with the inclined forward edge of the guard it shoves the latter to one side, the weight keeping the guard always against the timber and over the rotating knives, protecting the operator. When the timber has passed through the machine, it is placed on top of the guard and returned to its first position, the hands of the operator never coming near the knives. To compensate for 80 warping of the guard, a set screw 19 is put through the plate 10, and enables the guard 5 to be raised if desired.

Having thus explained the nature of the invention, and described an operative manner of constructing and using the same although without attempting to set forth all of the forms in which it may be made, or all of the forms of its use, what is claimed is:

A guard for planing machine, comprising 90 an attaching bracket, a plate secured by fastening elements to one end of the guard, a depending spindle rigid with said plate and journaled in said bracket for rotatably supporting the guard, an adjusting screw 95 threaded in said plate and engaging said guard, said set-screw being located in the plate relative to said fastening elements and said guard to adjust the latter relative to the plate in case of sagging, said spindle being elongated and slideable in said bracket to permit the insertion of shims to elevate the guard relative to said bracket.

In testimony whereof I affix my signature.

ODILON MAZURETTE.
